UNITED STATES PATENT OFFICE.

HARRY F. BUSHONG, OF KALAMAZOO, MICHIGAN, ASSIGNOR TO KALAMAZOO LOOSE LEAF BINDER COMPANY, OF KALAMAZOO, MICHIGAN.

TEMPORARY BINDER.

No. 878,340.

Specification of Letters Patent.

Patented Feb. 4, 1908.

Application filed December 31, 1906. Serial No. 350,267.

To all whom it may concern:

Be it known that I, HARRY F. BUSHONG, a citizen of the United States, residing at the city of Kalamazoo, county of Kalamazoo, State of Michigan, have invented certain new and useful Improvements in Temporary Binders, of which the following is a specification.

This invention relates to improvements in temporary binders, or loose leaf holders. It is particularly adapted to the style of binder illustrated and described in my application for Letters Patent, filed August 5th, 1904, Serial No. 219,624, and is a modification and, in some respects, an improvement on the structure there illustrated, although it is applicable for use in various relations.

The objects of this invention are, first, to provide an improved temporary binder or loose sheet holder which may be quickly and easily adjusted or manipulated to remove or insert the sheets; second, to provide an improved temporary binder or loose sheet holder adapted to securely retain any number of sheets or leaves, from one to its maximum capacity, which may be very quickly adjusted to permit the insertion or removal or changing of any number desired of the leaves.

Further objects, and objects relating to structural details, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which,

Figure 1 is an inside plan view of a structure embodying the features of my invention, the covers being open and their inner walls partially broken away to show the relation of the parts. Fig. 2 is a detail section, taken on a line corresponding to line 2—2 of Fig. 3. Fig. 3 is an enlarged detail plan of the adjusting mechanism removed from the covers.

In the drawing, the sectional views are taken looking in the direction of the little arrows at the ends of the section lines, and similar reference characters refer to similar parts throughout the several views.

Referring to the drawing, the covers 1 are preferably formed with chambers therein to receive the adjusting mechanism of the binder. The inner walls 2 of the covers are preferably of sheet metal on account of the strength and so that the covers may be made comparatively thin. In one of the covers, I arrange a ratchet or rack-bar 3, the same being preferably secured by screws 4 at each end to the outer wall. Slidably arranged on this rack-bar is a cross bar 5 to which the binding cords are secured at one end. The binding cords are secured at the other end to the cross-bar 7 mounted on the screw-threaded shaft 8, which is longitudinally arranged in the chamber of the opposite cover. The threaded shaft 8 is adapted to be manipulated by a key as is the case in my application for Letters Patent above referred to. The cross-bar 5 is provided with a seat above the rack 3 for the pawl 9. This pawl is preferably formed of a flat bar having its ends turned downwardly to embrace the cross-bar, its inner end projecting sufficiently to engage the teeth of the bar 3 when in its engaging position.

A blade spring 10 is secured by a horizontal pivot 14 to the cross-bar 5, its free end being adapted to swing over the pawl 9 and when in one position to hold the same in engagement with the rack-bar, and, when swung to its other position, to hold it out of engagement. Its position for holding the pawl out of engagement is indicated by the dotted lines in Fig. 1. By this arrangement, with the pawl in its engaging position, when the cross-bar 5 is moved outwardly it is held in its adjusted position by the pawl, and is locked against inward movement. When the pawl is disengaged the cross-bar may be moved freely back and forth on the ratchet bar. The spring 10 is provided with a button-like finger piece 15, adapted to be grasped through the slot 12 in the inner wall of the cover, for manipulating the spring.

A trigger-like finger piece 11 is pivoted on the cross-bar 5, the same being arranged through longitudinal slot 12 in the inner wall of the cover 2. By grasping this finger piece, the bar may be moved along the rack to tighten the binding cords. In books of sizes such as are in common use, it is possible to grasp the outer end of the cover with the fingers and the finger piece 11 with the thumb, so that the adjustment is easily ac-

complished and the binding cords drawn sufficiently tight to hold the sheets for ordinary purposes.

It is found in practice that the binding cords can by this means be drawn sufficiently tight for holding the sheets for ordinary manipulation. However, if it is desired to tighten them further, this can be readily done by means of the screw-shaft 8. It is intended in practice that the expansion or contraction of the binder to receive a large or small number of leaves shall be accomplished through the adjustment of the screw shaft 8; and that, when it is desired to open the book to change or insert or remove a small number of leaves, this can be accomplished by means of the ratchet mechanism described.

The finger piece 11 is preferably so arranged that it folds down through the slot 12 so that the inner wall of the cover is practically smooth. When it is desired to open the binder, the pawl spring 10 is swung into position to disengage the pawl. If the pawl 25 does not free itself on account of the strain thereon when thus released, a slight outward pull on the finger piece accomplishes the result. When it is desired to tighten the binder, the pawl spring is thrown into position to hold the pawl in engagement and the binding cords are tightened by means of the finger piece 11, as described.

My improved binder is capable of very rapid adjustment and can be adjusted to hold any desired number of leaves, from one to its maximum capacity. The same can be readily adjusted so that it will hold a very large number of leaves very securely, and it can be adjusted to hold any number of leaves from one up. The clamping bars 13 are, as stated, preferably those described in my application above referred to, and, as they are fully shown and described therein, I do not illustrate and describe the same in detail in this case.

I have illustrated and described my improved binder in detail in the form preferred by me on account of the structural simplicity and convenience in manipulation. I am, however, aware that it is capable of considerable variation in structural details without departing from my invention and I desire to be understood as claiming the same specifically, as illustrated, as well as broadly.

Having thus described my invention, what I claim as new and desire to secure by Letters Patent is:

1. The combination with the covers having chambers therein, the inner walls of one of said covers being provided with a slot, of binding cords; cross-bars to which said binding cords are secured arranged in said chambers in said covers; a ratchet-bar on which one of said cross-bars is slidably mounted

arranged in the cover having the slotted inner wall; a pawl seat on said cross-bar; a bar-like pawl having downturned ends adapted to embrace the said cross-bar arranged on said seat; a spring for said pawl pivoted on said cross-bar adapted to be adjusted to hold said pawl into or out of its engaging position; a finger-piece for said spring adapted to be manipulated through said slot in said cover; a finger-piece pivoted on said cross-bar arranged through the said slot on said cover, said finger-piece being adapted to fold down into said slot; and a longitudinally-arranged screw shaft for adjusting the other of said cross-bars, for the purpose specified. 80

2. The combination with the covers having chambers therein, the inner walls of one of said covers being provided with a slot; binding cords; cross-bars to which said binding cords are secured arranged in said chambers in said covers; a ratchet-bar on which one of said cross-bars is slidably mounted arranged in the cover having the slotted inner wall; a pawl seat on said cross-bar; a bar-like pawl having downturned ends adapted to embrace the said cross-bar arranged on said seat; a spring for said pawl pivoted on said cross-bar adapted to be adjusted to hold said pawl into or out of its engaging position; a finger-piece pivoted on said cross-bar through said slot on said cover; and a longitudinally-arranged screw shaft for adjusting the other of said cross-bars, for the purpose specified. 85

3. The combination with the covers having chambers therein, the inner walls of one of said covers being provided with a slot; binding cords; cross-bars to which said binding cords are secured arranged in said chambers in said covers; a ratchet-bar on which one of said cross-bars is slidably mounted arranged in the cover having the slotted inner wall; a pawl on said cross-bar; a bar-like pawl having downturned ends adapted to embrace the said cross-bar arranged thereon; a spring for said pawl adapted to be adjusted to hold said pawl into or out of its engaging position; a finger-piece for said spring adapted to be manipulated through said slot in said cover; a finger-piece pivoted on said cross-bar through the said slot on said cover, said finger-piece being adapted to fold down into said slot; and a longitudinally arranged screw shaft for adjusting the other of said cross-bars, for the purpose specified. 100

4. The combination with the covers having chambers therein, the inner walls of one of said covers being provided with a slot, of binding cords; cross-bars to which said binding cords are secured arranged in said chambers in said covers; a ratchet-bar on which one of said cross-bars is slidably mounted arranged in the cover having the slotted inner wall; a pawl on said cross-bar; a spring for said pawl adapted to be adjusted to hold 115

said pawl into or out of its engaging position; a finger-piece pivoted on said cross-bar arranged through the said slot on said cover; and a longitudinally arranged screw shaft 5 for adjusting the other of said cross-bars, for the purpose specified.

5. The combination with the covers having a chamber therein, the inner wall of said cover being provided with a slot, of binding cords; 10 a cross-bar to which the ends of said binding cords are secured arranged in said chamber in said cover; a ratchet on which said cross-bar is slidably mounted arranged in said cover; a pawl seat on said cross-bar; a bar-like pawl having downturned ends adapted 15 to embrace the said cross-bar arranged on said seat; a spring for said pawl pivoted on said cross-bar adapted to be adjusted to hold said pawl into or out of its engaging position; 20 a finger-piece for said pawl adapted to be manipulated through said slot in said cover; and a finger-piece pivoted on said cross-bar arranged through the said slot on said cover, said finger-piece being adapted to fold down 25 into said slot, for the purpose specified.

6. The combination with the cover having a chamber therein, the inner wall of said cover being provided with a slot, of binding cords; a cross-bar to which the ends of said 30 binding cords are secured arranged in said chamber in said cover; a ratchet on which said cross-bar is slidably mounted arranged in said cover; a pawl seat on said cross-bar; a bar-like pawl having downturned ends 35 adapted to embrace the said cross-bar arranged on said seat; a spring for said pawl pivoted on said cross-bar adapted to be adjusted to hold said pawl into or out of its engaging position; and a finger-piece pivoted 40 on said cross-bar arranged through the said slot on said cover, for the purpose specified.

7. The combination with the cover having a chamber therein, the inner wall of said cover being provided with a slot, of binding 45 cords; a cross-bar to which the ends of said binding cords are secured arranged in said chambers in said cover; a ratchet on which said cross-bar is slidably mounted arranged in said cover; a pawl carried by said cross- 50 bar; a spring for said pawl pivoted on said cross-bar adapted to be adjusted to hold said pawl into or out of its engaging position; a finger-piece for said pawl adapted to be manipulated through said slot in said cover; and 55 a finger-piece pivoted on said cross-bar arranged through the said slot on said cover, said finger-piece being adapted to fold down into said slot, for the purpose specified.

8. The combination with the cover having 60 a chamber therein, the inner wall of said cover being provided with a slot, of binding cords; a cross-bar to which the ends of said binding cords are secured arranged in said chamber in said cover; a ratchet on which 65 said cross-bar is slidably mounted; a pawl

carried by said cross-bar; a spring for said pawl pivoted on said cross-bar adapted to be adjusted to hold said pawl into or out of its engaging position; and a finger-piece pivoted on said cross-bar arranged through the 70 said slot on said cover, for the purpose specified.

9. The combination with the covers having chambers therein, of binding cords; 75 cross-bars to which said binding cords are secured arranged in said chambers in said covers; a ratchet-bar on which one of said cross-bars is slidably mounted arranged in one of said covers; a pawl carried by said cross-bar; means for disengaging said pawl; a 80 finger-piece on said cross-bar; and a screw for adjusting the other of said cross-bars, for the purpose specified.

10. The combination with the covers having chambers therein, of binding cords; 85 cross-bars to which said binding cords are secured arranged in said chambers in said covers; a ratchet-bar on which one of said cross-bars is slidably mounted arranged in one of said covers; a pawl carried by said 90 cross-bar; means for disengaging said pawl; and a screw for adjusting the other of said cross-bars, for the purpose specified.

11. The combination with the covers having chambers therein, of binding cords; 95 cross-bars to which said binding cords are secured arranged in said chambers in said covers; a ratchet-bar on which one of said cross-bars is slidably mounted arranged in one of said covers; a pawl carried by said 100 cross-bar; means for disengaging said pawl; a finger-piece on said cross-bar; and means for adjusting the other of said cross-bars, for the purpose specified.

12. The combination with the covers having chambers therein, of binding cords; 105 cross-bars to which said binding cords are secured arranged in said chambers in said covers; a ratchet-bar on which one of said cross-bars is slidably mounted arranged in 110 one of said covers; a pawl carried by said cross-bar; means for disengaging said pawl; and means for adjusting the other of said cross-bars, for the purpose specified.

13. The combination with the covers, one 115 of said covers having a chamber therein, of binding cords; a cross-bar to which said binding cords are secured arranged in said chamber in said cover; a ratchet-bar arranged in said cover; a pawl carried by said 120 cross-bar; means for disengaging said pawl from said ratchet-bar; and a finger-piece on said cross-bar, for the purpose specified.

14. The combination with the covers, one 125 of said covers having a chamber therein, of binding cords; a cross-bar to which said binding cords are secured arranged in said chamber in said cover; a ratchet-bar arranged in said cover; a pawl carried by said cross-bar; and means for disengaging said 130

pawl from said ratchet-bar, for the purpose specified.

15. The combination with the covers, of binding cords; cross-bars to which said binding cords are secured; a ratchet mechanism for securing one of said bars carried by one of said covers; means for disconnecting said ratchet mechanism; and a screw for adjusting the other of said cross-bars carried by 10 the opposite cover.

16. The combination with the covers, one of said covers having a chamber therein, and the inner wall of said cover having a slot therein; binding cords; an adjustable member to which said binding cords are connected; means for securing said adjustable member in its adjusted position in said cover; and a finger-piece pivoted on said adjustable member arranged through the slot in said cover, 20 said finger-piece being adapted to fold down into said slot, for the purpose specified.

17. The combination of the covers, one of said covers having a chamber therein and the inner wall of said cover having a slot 25 therein; binding cords; an adjustable member to which said binding cords are connected; means for securing said adjustable member in its adjusted position in said cover; and a finger-piece pivoted on said adjustable 30 member arranged through the slot in said cover, for the purpose specified.

18. The combination of the covers, one of said covers having a chamber therein; binding cords; an adjustable member to which 35 said binding cords are secured, arranged in said cover; means for securing said adjustable member in its adjusted positions; and a finger-piece pivoted on said member adapted to be swung down into the chamber 40 when not in use.

19. The combination with the covers, of binding cords; a cross-bar to which said binding cords are secured; a bar on which said cross-bar is slidably mounted carried by 45 one of said covers; and means for securing said cross-bar in its adjusted position on said bar.

20. The combination with the covers, of binding cords; cross-bars to which said cords 50 are secured; a bar on which one of said cross-bars is slidably mounted; means for automatically securing said cross-bar in its adjusted position on said bar; and a screw for adjusting the other of said cross-bars carried 55 by the opposite cover.

21. The combination with the covers, of binding cords; cross-bars to which said cords are secured; a bar on which one of said cross-bars is slidably mounted; and means for

automatically securing said cross-bar in its 60 adjusted position on said bar.

22. The combination with the covers, of binding cords; cross-bars to which said binding cords are secured arranged to be adjusted in said covers; means for securing 65 one of said bars in its adjusted position adapted to be disengaged therefrom so that said cross-bar may be moved freely in said cover; and a screw for adjusting the other of said cross-bars carried by the opposite 70 cover.

23. The combination with the covers, of binding cords; cross-bars to which said binding cords are secured arranged to be adjusted in said covers; and means for securing 75 one of said bars in its adjusted position adapted to be disengaged therefrom so that said cross-bar may be moved freely in said cover.

24. The combination with the covers of 80 binding cords; a ratchet bar; an adjustable member mounted on said ratchet bar to which said binding cords are connected; a pawl carried by said adjustable member; and means for holding said pawl out of its 85 engaging position.

25. The combination with the covers, one of said covers having a chamber therein; binding cords; an adjustable member to which 90 said binding cords are secured, arranged in said chamber of said cover; means for securing said adjustable member in its adjusted position on said cover; and a finger piece 95 for said adjustable member arranged through the inner wall of said cover chamber and adapted to be swung down into the chamber when not in use.

26. The combination with the covers, one of said covers having a chamber therein, of binding cords; an adjustable member to 100 which said binding cords are secured, arranged in said chamber of said cover; means for securing said adjustable member in its adjusted position in said cover chamber, arranged to act automatically on the retracting 105 movement of the adjusting member, and a finger piece arranged upon said adjustable member, projecting from said chamber whereby said adjustable member may be manipulated from without the chamber.

In witness whereof, I have hereunto set my hand and seal in the presence of two witnesses.
